UNITED STATES PATENT OFFICE.

ECKLEY B. COXE, OF DRIFTON, PENNSYLVANIA.

COAL-BREAKING APPARATUS.

SPECIFICATION forming part of Letters Patent No. 527,412, dated October 16, 1894.

Application filed May 19, 1894. Serial No. 511,778. (No model.)

To all whom it may concern:

Be it known that I, ECKLEY B. COXE, a citizen of the United States, residing at Drifton, in the county of Luzerne and State of Pennsylvania, have invented certain new and useful Improvements in Coal-Breaking Apparatus, of which the following is a specification.

This invention relates to coal-breaking apparatus and is in the nature of an improvement upon the coal-breaking apparatus described and claimed in an application for United States Letters Patent filed by me May 19, 1894, Serial No. 511,551; the object of my present invention being to provide an apparatus especially adapted for breaking and handling anthracite coal; and to provide in connection with the revolving break-rolls of the apparatus, means for receiving the broken coal as it is discharged from said break-rolls and for carrying the same away with the minimum amount of loss due to fractional breakage or partial disintegration.

My present invention resides in an apparatus comprising a pair of break-rolls revolvably connected together, means for driving said rolls, means for feeding coal to said rolls, and a discharge-conveyor located below said rolls and having an elastic or brush-like coal-receiving surface adapted for cushioning the blow of the coal as it drops from the rolls, as will be hereinafter more fully described.

In the drawings accompanying and forming a part of this specification, Figure 1 represents in sectional side elevation a coal-breaking apparatus embodying my present invention.

Fig. 2 is a similar view of a portion of the apparatus shown in Fig. 1, said figure showing the discharge-conveyor provided with one form of tension-device. Fig. 3 is a sectional side elevation of a portion of a modified form of apparatus. Figs. 4 and 5 are enlarged sectional details of a portion of two forms of conveyor-belt embodying my invention.

Similar characters designate like parts in all the figures.

The coal-breaking apparatus shown in the drawings consists of a frame, A, which may be of any suitable construction for carrying the operative parts; two adjacent break-rolls, B and B', revolvably connected together for coincident movement; two carriers or convey-

ers, C and C', one of which is located with its discharge-end above and remote from the break-rolls and is adapted for delivering the lumps of coal separately and successively to the rolls with a falling movement of predetermined maximum velocity, and the other of which is in the nature of a flexible belt or apron having an elastic nap, or brush-like coal-receiving surface, adapted to receive the coal and cushion the blow thereof as it drops from the rolls, and means for rotating the break-rolls at a peripheral velocity substantially coinciding with the maximum velocity of the falling coal and for imparting a traveling movement to one or both of the conveyers, as will be hereinafter more fully described.

The break-rolls B and B', which may be of any usual or suitable form, are herein shown as the ordinary fluted rolls with V-shaped breaking-ribs or teeth, 6, said rolls being shown carried by horizontally-disposed shafts, 2 and 2', journaled in bearings upon the frame A, and connected together for coincident movement by intermeshing gear-wheels 4 and 4', (indicated by dotted circles) which gear-wheels are, or may be, secured to the shafts 2 and 2' in any suitable manner. A hopper, 7, is shown provided with its discharge-end adjacent to the upper edges of the rolls and in position to insure the delivery of the lumps of coal between the rolls in case any of the lumps should be accidentally thrown out of alignment with the faces of said rolls.

In the preferred form thereof herein shown, one or both of the two conveyers C and C' may be in the nature of endless traveling belts, the one C being located with its discharge-end, 8, above and remote from the two break-rolls B and B', said endless conveyor being carried over pulleys or rollers, 9 and 9', secured to shafts 10 and 10' respectively; the shaft 10, in the organization herein shown, constituting the main driving-shaft. The conveyor C' is located with its receiving-end, 11, below and in near proximity to the break-rolls B and B'; this conveyor-belt C' being carried over the pulleys or rollers 12 and 12', secured upon the shafts 13 and 13'. The shafts 10 and 10', 13 and 13' will, in practice, be supported in suitable bearings at

their ends, which bearings may be secured to, or form a part of, the framework A, a portion only of which framework is shown in the drawings.

- 5 In the drawings, the rolls B and B' and the two conveyers C and C' are shown driven from the main shaft 10, said shaft being driven by means of a belt, 14, extending over a pulley upon the main shaft and extending to 10 any suitable source of power. (Not shown.) A belt, 15, extends from the pulley 16 upon the main shaft over a pulley, 17, upon the shaft 13 of, and imparts a traveling movement to, the conveyer C'; and another belt, 18, extends from a pulley, 19, upon the main shaft over a pulley, 20, upon the break-roll shaft, 2, which furnishes power for driving the two break-rolls.

It will be obvious that the general organization of the two conveyers and break-rolls may be modified without departing from my invention.

For convenience, the upper conveyer-belt will be herein referred to as the "feed-conveyer;" and the lower conveyer-belt will be referred to as the "discharge-conveyer."

The feed-conveyer, C, will be supplied with lumps of coal, 24, from a hopper or chute, 21, located adjacent to the receiving-end of said 25 conveyer, and will, in practice, preferably be set at an inclination to a horizontal line, as illustrated in the drawings, with its discharge-end just far enough above the break-rolls that when a lump of coal 24' falls from 30 the discharge-end of the belt it will descend with an increasing velocity, the maximum of which velocity (or its velocity when it reaches the break-rolls, as at 24'') shall equal or approximately equal the peripheral velocity of 35 the feed-rolls, which rolls will, in practice, be rotated at a certain given peripheral velocity. The coincidence in velocity of the falling coal at the time it reaches the rolls and the peripheral velocity of said rolls may be readily 40 established after the well-known manner of measuring the velocities of falling and revolving bodies, the distance through which the coal travels after leaving the feed-conveyer being gaged by the height of the feed-conveyer 45 with relation to the break-rolls to insure a maximum velocity to the lumps of coal which will coincide with the peripheral velocity of the break-rolls.

By the employment of a continuously-traveling belt, as shown and described, for feeding the lumps of coal to the break-rolls, the lumps of coal are delivered to the rolls separately and with uniform speed; and in consequence of the acquired velocity of each 55 lump, when it reaches the break-rolls, being substantially equal to the peripheral velocity of said rolls, said lump does not strike a blow against the teeth of the rolls as it enters the same, but is grasped sidewise by the rolls, 60 broken thereby, and carried through said rolls without affecting or decreasing the ve-

locity acquired by said lumps before entering the rolls. Thus it will be seen that the lumps are successively and separately subjected to the action of the break-rolls, (one 70 lump being broken before the next succeeding lump enters the rolls,) thus preventing the liability of crowding the rolls by feeding the coal faster than the rolls can break it, and also obviating fractional breakage, by preventing the lumps from striking against each other and against the teeth of the rolls while being fed thereto.

The means for receiving and carrying away the coal as it is discharged from the break-rolls constitutes an important factor in my present invention. This means consists of the discharge-conveyer C' and the mechanism in direct connection therewith.

In the drawings I have shown several forms 85 of discharge-conveyers, all of which are within the scope of my present invention. In the preferred form thereof shown most clearly in Figs. 1 and 2, this conveyer consists of the endless belt C', the outer or coal-receiving 90 face, 25, of which is tufted or of brush-like construction, it being in the nature of a mat having its tufts or fibers set at right angles to the plane of the web, thus forming a "cut-pile" surface for cushioning the blows of the 95 lumps of coal as they drop to the conveyer from the break-rolls. The conveyer-belt C' will preferably be set at an inclination to a horizontal line, as shown in the drawings, and will have a continuous traveling movement 100 imparted to it in excess of the traveling movement of the feed-conveyer and of sufficient rapidity to carry the lumps of coal away from the line of delivery before the next succeeding lumps are discharged from the 105 break-rolls. Owing to the peculiar construction of the coal-receiving surface of the conveyer and the arrangement of said conveyer with relation to the break-rolls as described, the pieces of coal will strike the fibers, or 110 brush-like ends, of the surface of the conveyer obliquely, causing them to yield or spring laterally, thereby cushioning the blow of said pieces. This yielding or springing action of the brush-like ends or fibers of the 115 conveyer, laterally of themselves, taken in connection with the downward traveling movement of the said conveyer, operates, in practice, to gradually take up the momentum of the falling coal without occasioning any 120 material rebound of the same, thereby preventing the striking of one piece against another with any injurious force, and obviating the fractional breakage or partial disintegration common to coal-breakers of ordinary construction.

The discharge-conveyer may be made of various materials. One of the preferred forms, shown in Fig. 5, will be similar to woven velvet, but made of iron rods, 26, connected 130 together in the form of a chain or apron and carrying pieces of rope, 27, whose free ends

form the fiber or brush-like receiving-surface of the conveyer. It is desired to state in this connection that I do not desire to limit myself to the particular forms of conveyer shown in Figs. 1, 2, 4 and 5, as these might be modified without departure from my invention.

It is desirable to keep the receiving-side of the conveyer somewhat taut and at the same time permit said conveyer to have some curvature under the rolls and to yield slightly to the blows of the falling coal. To accomplish this end, I have shown in connection with said conveyer means for drawing the receiving-side thereof taut and at the same time permitting the tension to be regulated to suit circumstances. This means, in the form shown in Fig. 2, consists of a weight, W, carried by a roller, 30, resting upon the lower run of the endless conveyer C'. This will be the preferred form of tension - device employed in connection with an endless conveyer, as it does not interfere with the continuous travel of the conveyer and will readily draw the upper run taut with the requisite tension.

In Fig. 3, I have shown the discharge-conveyer C' in the nature of an inclined apron fixed at one end to the framework and adjustably carried at its opposite end upon the curved face, 31, of a lever, 32, fulcrumed at 33 upon the frame and carrying a weight, W, at its outer end, by means of which weight said apron is held taut with the required tension. This tension may be regulated as is necessary, according to the nature of the coal and the weight to be sustained, by moving the weight W toward or from the outer end of the lever 32, as will be understood by reference to said Fig. 3.

Having thus described my invention, I claim—

1. In a coal-breaking apparatus, the combination with a pair of revolute break-rolls and with means for delivering coal thereto, of a discharge-conveyer located below said rolls and having an elastic or brush-like receiving-face, and means for imparting a traveling movement to said conveyer, substan-

tially as described and for the purpose set forth.

2. In a coal-breaking apparatus, the combination with a pair of co-acting break-rolls, of a flexible discharge-conveyer located below said rolls, and a tension-device in connection with said conveyer, substantially as described and for the purpose set forth.

3. The herein-described coal-breaking apparatus, it consisting of a pair of break-rolls revolubly connected, a feed-conveyer located above said rolls, a flexible discharge-conveyer located below said rolls, means for regulating the tension of said discharge-conveyer, and means for imparting movement to the rolls and to one or both of the conveyers, substantially as described and for the purpose set forth.

4. The herein-described coal-breaking apparatus, it consisting of a pair of co-acting break-rolls, a feed conveyer located with its discharge-end above and remote from the break-rolls, an endless discharge-conveyer located with its receiving end below and adjacent to said rolls and having a tufted or brush-like coal-receiving surface, the fibers of which are adapted to yield laterally with relation to each other to cushion the blow of the coal as it drops from the break-rolls, and means for imparting a traveling movement to the conveyers and for rotating the rolls, substantially as described.

5. In a coal-breaking apparatus, the combination with a pair of co-acting break-rolls, and with means for delivering coal thereto, of a discharge-conveyer located below said break-rolls and consisting of an endless flexible belt having a tufted or brush-like coal-receiving face, the fibers of which project at right angles to the plane of the body of the belt, means for driving said belt, and means for drawing the same taut, substantially as described.

ECKLEY B. COXE.
